UNITED STATES PATENT OFFICE.

HENRY J. WEPPLO, OF MINNEAPOLIS, MINNESOTA.

AIR PUMP.

Application filed February 27, 1925. Serial No. 12,088.

This invention relates to improvements in air pumps and particularly to those of the hand-operated type used to inflate a pneumatic tire of an automobile or bicycle.

5 A particular object of this invention is to provide a manually operated reciprocating pump having means whereby the operator may use foot power on the downward movement of the piston and the device embodies 10 improvements in the pump for a similar purpose shown and described in my pending application #736,626, filed September 8, 1924.

The invention consists generally in various 15 constructions and combinations all as hereinafter described and particularly pointed out in the claims.

In the accompanying drawings forming part of this specification,

20 Figure 1 is a vertical sectional view through a hand and foot operated pump embodying my invention;

Figure 2 is a transverse sectional view on the line 2—2 of Figure 1;

25 Figure 3 is a transverse sectional view on the line 3—3 of Figure 1;

Figure 4 is a sectional view on the line 4—4 of Figure 1;

30 Figure 5 is a detail of the plunger head or piston.

In the drawing, 2 represents the base of the pump having on one side a hinged foot piece 3 adapted to swing down to a horizontal position to receive the foot during the 35 pumping operation and adjacent to this hinged foot piece is a hose 4 leading from a passage 5 in the base to the tire to be inflated. 6 represents the pump barrel and 7 is a piston rod on which the piston head or 40 plunger is mounted. This head or plunger comprises an upper disk 8 and a lower disk 9 between which the flexible packing disk of suitable material such as leather 10 is held, the edges of the disk bearing on the inner 45 walls of the barrel as usual in devices of this kind. One side of the lower disk is cut away as indicated at 11 in Figure 5 so that the flexible disk is unsupported on the upward movement of the plunger and will 50 therefore swing down to the position indicated by dotted lines in Figure 1 and allow the plunger to move easily in the barrel and at the same time permit the free flow of air from the upper portion of the barrel to the 55 space beneath the plunger. Upon the down stroke of the plunger, the flexible disk will

move outwardly against the walls of the barrel and be seated against the upper disk 8. The lower disk 9 serves in effect as a flapper valve on the down stroke of the plunger providing a quicker closure of the barrel. With the old type of leather cup and washer, when the cup became worn and dry the plunger head would have to move sometimes 6 or 8 inches before the pressure was sufficient to 60 expand the cup against the walls of the barrel.

At the top of the barrel is a cap or cover 12 having an opening 13 therein in which the plunger rod 7 is adapted to slide. An 70 extension 14 is provided on one side of the cap 12 and in this extension a rod 15 is slideable parallel with the plunger rod but outside the barrel. The lower end of the rod 15 has an outwardly turned part 16 forming 75 a foot piece or rest for the foot of the operator and near this foot piece preferably the rod has a loop 17 which loosely encircles the pump barrel and is freely slideable thereon forming with the pump barrel a 80 vertical guide for the rod 15. The base 2 has preferably an extension 18 beneath the foot piece 16 and forming a stop therefor and I prefer to provide a bar 19 in this base and a strap 20 which encircles the bar and 85 the foot piece 16 and has the function of locking the rod and plunger in a depressed position so that the pump can be conveniently packed or stored away in the tool box of an automobile. When the pump is to 90 be used, the strap will of course be loosened to allow the free reciprocation of the rod 15 and the plunger. The upper end of the rod has an angled extension 21 which overhangs the pump barrel and this extension 95 has an orifice 22 in alignment with the plunger rod and adapted to receive the upper end thereof and wherein said rod is secured by suitable means. The cap or cover 100 12 is readily removable from the pump barrel and when released will allow convenient access to the barrel and the plunger therein. This cap, with the extension thereon, serves to guide the pump plunger vertically but prevents rotary or swinging movement of 105 the operating rod 15 around the barrel.

In using the pump, the operator will grasp the angled upper end of the rod 15 and put one foot on the extension 16 at the lower end of the rod and the downward stroke of 110 the plunger, usually accomplished laboriously by the hands and arms will be easily

effected by the power obtained through the pressure of the foot on the operating rod. On the up stroke the hands and arms may be utilized merely to raise the plunger and 5 the foot. With the manner shown of connecting the plunger rod with the operating rod, the attendant does not have to direct any of his attention to the guiding of the moving parts of the pump or in preventing 10 them from swinging around the pump barrel, the rod 15 being positively held by the guide on the upper end of the pump barrel and while it may slide freely vertically in said guide it cannot swing around the barrel and move the foot piece 16 to a position 15 out of alignment with the extension of the base.

I claim as my invention:

1. The combination with a pump barrel 20 and a plunger and rod therefor, of an operating rod arranged outside of said barrel and having an extension adapted to encircle the barrel and slide thereon, the upper end of said operating rod having an angled extension 25 forming a hand grip overhanging said pump barrel, said angled extension having an orifice therein and said plunger rod having its upper end removably secured in said orifice, a guiding means for said operating

rod on the upper end of said barrel, the 30 lower end of said operating rod having a footpiece to receive the foot of the operator, the pressure of the hand of the operator on said hand grip being in line with and exerted or transmitted directly to said plunger 35 rod.

2. The combination with a pump barrel and a plunger therefor, of two rods, one forming the plunger rod and connected at its lower end to the plunger and projecting 40 upwardly through and beyond the top of said barrel, the other forming an operating rod and having oppositely projecting angled extensions at its ends, one extension forming a footpiece at the lower end of the rod 45 and having a guiding means adapted to encircle and slide on said barrel, the other extension overhanging the top of the barrel and intersecting the axis of said plunger rod and having means for connection therewith, said operating rod having a guiding means at the top of said barrel and said rods being in adjacent parallel relation, the guiding means for said operating rod eliminating 50 lateral or side strains thereon. 55

In witness whereof, I have hereunto set my hand this 21st day of February, 1925.

HENRY J. WEPPLER.
